UNITED STATES PATENT OFFICE

101,510

DESIGN FOR AN AUTOMOTIVE BUMPER BAR

Laszlo M. Stempel and William E. Saxton, Coraopolis, Pa., assignors to Standard Steel Spring Company, Coraopolis, Pa., a corporation of Pennsylvania

Application July 16, 1936, Serial No. 63,884

Term of patent 7 years

To all whom it may concern:

Be it known that we, Laszlo M. Stempel and William E. Saxton, citizens of the United States, and residing at Coraopolis, in the county of Allegheny and State of Pennsylvania, U. S. A., have invented a new, original, and ornamental Design for an Automotive Bumper Bar, of which the following is a specification, reference being had to the accompanying drawing, forming a part thereof, wherein:

Figure 1 is a plan view of a bumper showing our

present design; Figure 2 is a front elevation of the same; Figure 3 is a sectional view on line III—III of Figure 2; Figure 4 is a sectional view on line IV—IV of Figure 2; and Figure 5 is a sectional view on line V—V of Figure 2.

We claim:

The ornamental design for an automotive bumper bar, substantially as shown.

LASZLO M. STEMPEL.
WILLIAM E. SAXTON.
